UNITED STATES PATENT OFFICE

2,447,764

PAINTBRUSH SUSPENSION

Henry C. McCain, Compton, Calif., assignor of
fifty per cent to Arthur L. Hughes, Walnut
Park, Calif.

Application October 26, 1945, Serial No. 624,797

2 Claims. (Cl. 248—360)

1

My invention relates to paint brushes and has for an object to provide means whereby a brush may be suspended over a paint container.

Another object of this invention is to provide a paint brush upon the head of which is supported a spring actuated clip.

A further object of this invention is to provide a spring pressed clip which may be attached to a paint brush whereby the same may be suspended over a drip pot or a paint can from various positions of the brush.

Other features and advantages will become more readily apparent from the following description and the accompanying illustrative drawings in which:

Figure 1 is an elevational view of my invention shown in operative position,

Figure 2 is a detail plan view of one form of the invention.

In the above drawings as well as in the specification to follow, the same characters of reference indicate the same parts throughout.

In the accompanying drawings 10, indicates my invention applied to a paint brush 11, and secured thereto by means of screws 12 and 13, upon which are coiled springs 14 and 15, which bear upon the collar 16, seated over the shank 17, of said brush. The collar has projecting from opposing sides thereof fingers 18 and 19, each of which is provided with a transverse groove 20 and 21, respectively, adapted to engage a rim 22, of a paint or other vessel 23, whereby the said fingers may be quickly slipped over the said rim and be secured thereto through the action of one or the other of said springs 14 and 15. It is obvious that I may also provide the member 16, with transversely arranged fingers 24, whereby if desired the brush may be held flat-wise over the said vessel instead of edge-wise as illustrated. The finger 24, is illustrated only in Figure 1 of the drawings.

Painters have great difficulty in keeping their brushes out of paint cans in order to prevent the absorption of too much paint when the brush is not in use. Therefore, I have provided the above described invention which will hold the brush suspended above the paint whereby its drippings will return to the paint can.

It is thought that persons skilled in the art to which the invention relates will be able to obtain a clear understanding of the invention after considering the description in connection with the

drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

- 10 1. In combination with a paint brush having a brush head and handle formed with a cylindrical bearing shank, guide screws adjustably secured in said brush head at the opposite sides of said bearing shank, a collar slidably disposed about said bearing shank being formed with diametrically opposed apertures for receiving said guide screws, integral oppositely extending clamping arms on said collar adapted to clamp over the upper rim of a paint can to hold the paint brush suspended thereover, and resilient tensioning means disposed about said guide screws between said clamping arms and the outer ends of said screws for tensioning said clamping arms.
- 25 2. In combination with a paint brush having a brush head and handle formed with a cylindrical bearing shank, guide screws adjustably secured in said brush head at the opposite sides of said bearing shank, a collar slidably disposed about said bearing shank being formed with diametrically opposed apertures for receiving said guide screws, integral oppositely extending clamping arms on said collar formed with arcuate seats adapted to clamp over the upper rim of a paint can with the rim of said can received in said seat for holding the brush suspended over the paint can, and adjustable resiliently tensioned means disposed about said guide screws between said clamping arms and the outer ends of said screws, whereby either end of said paint brush head may be supported on the rim of a paint can.

HENRY C. McCAIN.
